(57) **CLAIM**

The ornamental design for the ant bait station, as shown.

DESCRIPTION

FIG. 1 is a top, front and left side perspective view of an ant bait station in accordance with the present design;

FIG. 2 is a top plan view thereof;

FIG. 3 is a left side view thereof, which due to symmetry is the same as the right side, the front elevation, and the rear elevation views;

FIG. 4 is a bottom plan view thereof;

FIG. 5 is a bottom, rear and right side perspective view thereof;

FIG. 6 is a cross sectional view of FIG. 1, shown along lines 6-6 indicated in FIG. 2;

FIG. 7 is a top, front and left side perspective view of an ant bait station in accordance with a second embodiment of the present design;

FIG. 8 is a top plan view thereof;

FIG. 9 is a left side view thereof, which due to symmetry is the same as the right side, the front elevation, and the rear elevation views;

FIG. 10 is a bottom plan view thereof;

FIG. 11 is a bottom, rear and right side perspective view of the ant bait station shown in FIG. 7;

FIG. 12 is a cross sectional view of FIG. 7, shown along lines 12-12 indicated in FIG. 8;

FIG. 13 is a top, front and left side perspective view of an ant bait station in accordance with a third embodiment of the present design;

FIG. 14 is a top plan view thereof;

FIG. 15 is a left side view thereof, which due to symmetry is the same as the right side, the front elevation, and the rear elevation views;

FIG. 16 is a bottom plan view as shown in FIG. 13;

FIG. 17 is a bottom, rear and right side view thereof; and,

(Continued)

FIG. 18 is a cross sectional view, shown along lines 18-18 indicated in FIG. 14.
